DESIGN FOR AN ELASTIC TEXTILE FABRIC

Irving Weisberger, New York, N. Y.

Application March 10, 1938, Serial No. 75,716

Term of patent 3½ years

To all whom it may concern:

Be it known that I, Irving Weisberger, a citizen of the United States of America, residing in the city of New York, county of New York, and State of New York, have invented a new, original, and ornamental Design for an Elastic Textile Fabric, of which the following is a specification, reference being had to the accompanying drawing, forming part thereof.

The figure on the drawing is a plan view of an elastic textile fabric, showing my new design.

I claim:

The ornamental design for an elastic textile fabric, substantially as shown.

IRVING WEISBERGER,
